(57) **CLAIM**

The ornamental design for a foldable solar panel, as shown and described.

DESCRIPTION

FIG. 1 is a perspective view of a foldable solar panel showing our new design;

FIG. 2 is top plan view thereof;

FIG. 3 is a bottom plan view thereof;

FIG. 4 is a right side elevational view thereof;

FIG. 5 is a left side elevational view thereof;

FIG. 6 is a front elevational view thereof;

FIG. 7 is a rear elevational view thereof; and,

FIG. 8 is a perspective view thereof in the folded configuration.

The broken line shown in FIG. 1 is included for the purpose of illustrating unclaimed environment and forms no part of the claimed design.
